DRY CLEANING MACHINE

Russell Creighton, Kenmore, and Thomas H. Speller, Buffalo, N. Y., assignors, by mesne assignments, to The American Laundry Machinery Company, Cincinnati, Ohio, a corporation of Ohio

Application January 8, 1949, Serial No. 69,938

2 Claims. (Cl. 68—18)

1

This invention relates to dry cleaning apparatus for cleaning fabrics and the like with volatile solvents and particularly to apparatus of this class which is known as the closed type.

In closed type dry cleaning machines the several steps incident to effecting a cleaning cycle of operation are accomplished with the fabric materials, such as clothing or the like, remaining continuously in a single drum during the successive steps which comprise, generally, washing, extraction of the solvent, and reclaiming of residual solvent by passing warm air through the drum chamber.

In dry cleaning machines of the so-called closed type, the dirty solvent from the drum chamber discharges into a tank which may be conveniently located in the base of the machine beneath the drum. From this tank solvent is pumped to a filter unit which may be mounted on the same base as the drum but which, in the present instance, is preferably located separately from such base so as to be isolated from the vibration of the machine. From the filter unit the clean solvent is delivered back to the chamber which contains the drum so that it discharges against the drum continuously during the washing operation to replenish the solvent supply in the drum chamber.

In dry cleaning machines of the prior art it has been the practice, at the completion of the washing phase of the cycle of operation, to operate certain valves which by-pass the solvent coming from the filter so that it is returned to the tank and continuously re-filtered during subsequent operations. After washing the drum is rotated rapidly to extract the solvent centrifugally with the drum chamber opened to drain into the tank.

In the subsequent reclaiming operation of machines of this character, warm air is blown through the clothes in the drum after centrifugal extraction has taken place in order to recover the residual solvent from the garments, in vapor form, whereupon it is condensed and returned to the tank for subsequent filtration and reuse. This reclaiming operation has conventionally been practiced by closing off the drum and the reclaiming still or the like from the solvent reservoir or tank and the filter unit.

We have found that a much simpler and more efficient dry cleaning machine results when the several valves involved in closing off the reclaiming circuit from the filtering and washing circuit and the valves which are employed in bypassing the drum chamber to continuously filter

2

solvent during subsequent operations are entirely eliminated. It has heretofore been considered unfeasible to wash with the washing chamber in free and open communication with the passages which take part in the reclaiming cycle of operation, such passages being principally the intake to the fan or blower and the chamber containing the distilling and condensing heat exchangers which accomplish reclamation of vaporized solvent.

It has further been found, according to the present invention, that by providing a filter of such efficiency and capacity that a single flow therethrough of used solvent is sufficient to place it in condition for satisfactory reuse, an arrangement is provided wherein the filter itself is in free and continuous communication with the wash chamber. That is, the discharge conduit from the filter leads directly to the wash chamber and, in normal use of the device throughout the dry cleaning cycle, there is no necessity for cutting off this communication or establishing any alternative by-pass conduit from the outlet side of the filter. It is thus merely necessary to arrange for the solvent pump to be de-energized at the conclusion of the washing cycle, whereupon filtration ceases until the beginning of the next subsequent washing cycle.

The elimination of the various valves heretofore considered necessary in a machine of this class is, of course, important because of the economy and simplicity of design, but is of more importance than would be the case in some other classes of machines because of the tendency of valves in a dry cleaning machine to become clogged and inoperative by reason of accumulation of lint and the like. The elimination of moving parts such as valves and valve operators is also of greater importance in dry cleaning machines because of the corrosive effects of certain of the chemical reagents employed in the machines as detergents.

Various other objects and advantages which flow from employing the principles of the present invention will appear to those skilled in the art from a consideration of the following detailed description and the accompanying drawing which together set forth one exemplary form of apparatus embodying the principles of the present invention. It is to be understood, however, that the scope of the invention is not limited to the form shown by way of example or otherwise than as defined in the appended claims.

The single figure of the drawing is a front elevational view, principally in cross-section, of a

dry cleaning machine, showing in one form a practical application of the principles of the present invention.

The base upon which the machine generally is supported comprises a generally rectangular tank 10. The manner in which tank 10 is mounted upon a floor or the like to eliminate vibration of the machine or, more properly, to eliminate transmission of such vibration to a building housing the machine, forms no part of the present invention and it is illustrated in detail in a copending application of Dario Anselmo, Serial No. 2,628, filed January 16, 1948.

As is generally conventional in machines of this class the washing apparatus proper comprises upper and lower housings 11 and 12, respectively, which form split bearing parts for rotatably supporting a conventional peripherally perforated washer drum 13. The lower housing member 12 is provided with an integral arcuate wall portion 14 which defines the lower part of the drum chamber and forms a vat for holding cleaning solvent through which drum 13 rotates during the washing cycle. Wall 14 is provided at its bottom with a flap valve 16, which opens automatically at the conclusion of a washing cycle to dump the solvent from the vat into tank 10.

Operation of valve 16 and the timing and starting and stopping of the several phases of a complete cycle of dry cleaning, and the control of the various motors which enter into such cycle is by means of automatic timing and control mechanism not disclosed herein but illustrated and described in detail and claimed in a copending patent application of Theodore G. Mueller, Serial No. 25,617, filed May 7, 1948, now Patent No. 2,560,516.

It is further to be understood that various connections and conduits extend between the tank, the filter and other units of the machine, but these conduits are closed during normal machine operation and are only opened by means of manual valves for clean-out and draining purposes and for occasional special purpose use, but the present disclosure and invention concerns itself primarily with the main solvent circuit and the warm air reclaiming circuit which are normally employed in the principal operation of the machine. In this normal operation of the machine of the present invention, the only periodic opening and closing of a valve is valve 16 which is controlled by the timing mechanism referred to in the preceding paragraph.

In the drawing the numeral 18 designates a centrifugal solvent pump which is located near the bottom of tank 10 and has an operating motor 19 mounted upon tank 10. The outlet conduit of pump 18 is designated 21 and extends to the bottom of the filtering portion of a filter unit 20, conduit 21 being normally open in the usual operation of the machine throughout its cleaning, extracting, and reclaiming steps. The upper outlet portion of filter unit 20 has an outlet conduit 22 through which filtered solvent is led to the upper housing 11 where it discharges as at 25 to be directed against the perforated periphery of drum 13.

The filter unit 20 may be similar to that shown in detail in United States Letters Patent No. 2,328,565 to John E. Martin, granted September 7, 1943. The conduit designated 27 in the drawing is the equivalent of the conduit 129 of the Martin patent and is one of those used only occasionally when the filter is being drained back to the tank.

The arcuate wall 14 meets the wall of lower housing 12 at one side and at its other side terminates short of the wall of housing 12 as at 30 in the drawing. An auxiliary wall supports this end of arcuate wall portion 14 and is designated 31 and is provided with a normally open flap valve 32 which is closed only for special purposes not entering into present considerations. Thus, during the washing cycle filtered solvent is continuously fed against drum 13 and thus into the vat formed by arcuate wall portion 14 and the height of the bridge or dam formed by the portion 30 of wall 14 determines the depth of solvent in the vat through which the drum rotates. Excess solvent is substantially continuously spilling over such bridge and through the open passage in wall 31 past the normally open valve 32, from whence it falls into tank 10 where it is again ultimately picked up by pump 18 and fed to the filter.

During the washing operation a relatively small motor 35 operating through a reduction drive, including belts 36 and 37, rotates drum 13 at a relatively slow speed. At the conclusion of the washing cycle a larger and more powerful motor 38 operating only through the belt drive 37 and thus rotating drum 13 at a much greater speed operates to centrifugally extract solvent from the articles in drum 13 by reason of the high speed rotation. This motor arrangement is conventional, the larger motor 38 having free wheeling connection with the intermediate shaft 40 which is rotated by either of the motors and, in turn, rotates the mounting shaft 41 of drum 13.

At the conclusion of the extraction cycle, the large motor 40 stops and the smaller motor 35 again rotates drum 13 at a relatively slower speed during the solvent reclaiming period. During both the extracting and reclaiming cycles solvent pump motor 19 is inactive and there is no flow of solvent in the solvent circuit including the tank 10, filter unit 20 and the drum chamber.

At the beginning of the reclaiming cycle an air displacement fan 43 is set into operation by energization of its driving motor 44, and fan 43 draws air from within the drum 13 and the generally cylindrical chamber in which it is housed and through a passage 45 formed in upper housing member 11. An outlet portion 46 of a fan housing 47 directs the solvent bearing air against a heat exchanger 50 through which a cooling fluid is circulated as, for instance, the ordinary city water supply in most instances.

This causes the solvent suspended in the air passing over the heat exchanger to condense and fall into a trough formation 48 in upper housing member 11 and drain into a conduit indicated at 49 which leads to a gravity type solvent-water separator (not shown), the solvent being subsequently returned to tank 10. After the air passing through the upper portion of upper housing 11 has thus been rid of all or most of its cleaning solvent, it passes through a second heat exchanger 51 through which steam or the like is circulated so that the air is then heated and again passed through the drum chamber by virtue of a passage 52 formed in upper housing 11 by plates 53 and 54 which are fixed therein. It will be noted that air passage 52 and solvent conduit 25 are both in open and continuous fluid communication with the interior of the drum chamber.

What is claimed is:

1. In a dry cleaning machine, a drum chamber

and a rotatable material holding drum therein, a solvent tank beneath said chamber, a bridge wall in said chamber at one side of said drum to determine the level of solvent in said chamber, the space at the other side of said bridge wall having a normally open gravity drain passage to said tank, a filter unit and a pump for delivering solvent thereto from said tank, the upper portion of said drum chamber having an opening therein, an outlet conduit from said filter unit having open conduit connection with said drum chamber, and solvent reclaiming means including an air displacing fan having its intake side in open conduit connection with said drum chamber at the side opposite to said drum chamber opening and its outlet side directed into said drum chamber opening.

2. In a dry cleaning machine, a drum chamber and a rotatable material holding drum therein, a solvent tank beneath said chamber, a bridge wall in said chamber at one side of said drum to determine the level of solvent in said chamber, the space at the other side of said bridge wall having a normally open gravity drain passage to said tank, a filter unit and a pump for deliver- 25

ing solvent thereto from said tank, the upper portion of said drum chamber having an opening therein, an outlet conduit from said filter unit having open conduit connection with said drum chamber, solvent reclaiming means including an air displacing fan having its intake side in open conduit connection with said drum chamber at the side opposite to said drum chamber opening and its outlet side directed into said drum chamber opening, and means rendering said pump inoperative at the conclusion of a washing cycle whereby solvent does not flow in the filter circuit during operation of said reclaiming means fan.
